CATHODE FOR ELECTROLYTIC CELLS.

1,152,772.

Specification of Letters Patent.

Patented Sept. 7, 1915.

Application filed January 25, 1915. Serial No. 4,318.

To all whom it may concern:

Be it known that I, FRANK G. WHEELER, a citizen of the United States, residing at Appleton, in the county of Outagamie and 5 State of Wisconsin, have invented certain new and useful Improvements in Cathodes for Electrolytic Cells, of which the following is a specification.

This invention relates to perforated cathodes adapted for use in conjunction with a permeable diaphragm overlying the cathode, a primary object of the invention being to provide a structure of this type wherein the diaphragm, when used in an upright position, is effectively supported by the cathode over substantially its entire area, and wherein other advantages are secured, as will more fully appear hereinafter.

For a full understanding of the invention 20 reference is made to the accompanying drawings, showing certain preferred embodiments thereof, it being understood however that the invention is not restricted to the particular structural examples shown as illustrating 25 the same.

In said drawings—Figures 1, 2, 3, 4, and 6 are fragmentary cross-sectional views of several modifications of the invention; and Fig. 5 is a fragmentary elevation of the 30 cathode plate illustrated in Fig. 4, viewed from the rear.

In diaphragms intended for use in contact with a foraminous cathode plate, it has long been recognized that a merely marginal support of the diaphragm is in many cases insufficient; and it has been heretofore proposed to provide some form of bond between the diaphragm and the cathode for the purpose of supporting the former over its entire 40 area. For example, it has been proposed to provide the apertures of the cathode with marginal bars adapted to project into and support the diaphragm.

According to the present invention, the 45 diaphragm is supported by providing the cathode plate with apertures of such area that the diaphragm may enter them to such extent as may be necessary for its support when the cathode is placed in an upright position; and at the same time the rupture of the diaphragm is avoided by providing a suitable backing therefor at the rear of the apertures. For example, in Fig. 1, I have 50 shown a sheet-metal cathode 1, provided 55 with relatively large apertures 2, which may

be of any desired contour. The diaphragm is indicated at 3, overlying the cathode plate and entering the apertures 2. In this structure the rupture of the diaphragm at the apertures is prevented by a backing plate 4, 60 also of metal, but provided with smaller perforations 5. The backing plate may be perforated over its entire area, or only opposite the perforations 2, as may be most convenient. Electrically, the plates 1 and 4 together constitute the cathode, and this construction presents the great advantage that the conductivity of the cathode can be adjusted to suit current conditions quite independently of other considerations, as for example, by providing a thicker backing plate 65 when higher conductivity is required. Furthermore, the structure can be formed and adjusted accurately to design, to provide uniform conditions over the entire area. The 70 actual size of the apertures in the plate 1 will depend in a measure at least upon the thickness of the diaphragm. It is an advantage of the present structure that a wide 75 variation in the size of the apertures is permissible. 80

The backing plate may consist of wire cloth or screen having apertures smaller than those of the front plate, this construction being illustrated in Fig. 2, in which 4^a represents the wire cloth backing, the other numerals indicating the same elements as in Fig. 1. Or if desired both the front and 85 backing plates may consist of wire fabric, either in separate sheets or interwoven, the rear sheet having the finer mesh. Such construction is illustrated in Fig. 3, in which 1^b represents the coarser mesh fabric to which the diaphragm is applied, and 4^b the finer 90 mesh backing. For clearness of illustration 95 the diaphragm is omitted.

Figs. 4 and 5 show a modified construction in which the front plate and the backing elements are formed from a single sheet of metal, the perforations 2 which may be of 100 any desired shape or area, being cut around a portion only of their perimeter, as for example around three sides in the case of rectangular openings, and the attached tongues or flaps 6 displaced rearwardly to form the 105 backing element for the diaphragm 3. This construction requires less metal, is less expensive, and provides a very efficient support and backing for the diaphragm. Moreover, the actual aperture through the plate is 110

partially at an angle to the current flow, and therefore does not decrease the active cathode area to the same extent as when simple perforations are used. However, in this construction the conductivity of the cathode cannot be adjusted entirely independently of the thickness of the cathode plate.

Fig. 6 illustrates a further modification of the construction previously described, but having the tongues 6 perforated as indicated at 7.

Obviously, the construction may be variously modified without departing from the invention. The apertures in the front cathode plate may be rectangular, round, polygonal, etc., with any combination of apertures in the backing-plate. If desired, more than

two plates may be used, the size of the perforations in such case decreasing rearwardly, or in a direction away from the diaphragm. 20

I claim:—

In combination, a diaphragm, a perforated cathode, the perforations being of sufficient area to receive portions of the diaphragm and thereby effectively to support the latter, 25 and electrically conductive means located in the rear of said perforations for backing the diaphragm to prevent rupture.

In testimony whereof I affix my signature in presence of two witnesses.

FRANK G. WHEELER.
